United States Patent Office

Des. 192,548
Patented Apr. 3, 1962

192,548

PORTABLE INCINERATOR

Rallston M. Sherman, Glastonbury, Conn.

Filed Aug. 7, 1961, Ser. No. 66,227

Term of patent 14 years

(Cl. D81—1)

FIG. 2

FIG. 3

FIG. 4

FIG. 1 is a perspective view of a portable incinerator showing my new design;

FIG. 2 is a side elevation thereof; and

FIGS. 3 and 4 are top and bottom plan views, respectively, thereof.

I claim:

The ornamental design for a portable incinerator, substantially as shown.
